(57) **CLAIM**

The ornamental design for a personal security device, as shown and described.

DESCRIPTION

FIG. 1 is a front perspective view of a personal security device, showing novel design;

FIG. 2 is a rear perspective view of the personal security device of FIG. 1;

FIG. 3 is a front elevation of the personal security device of FIG. 1;

FIG. 4 is a rear elevation of the personal security device of FIG. 1;

FIG. 5 is a right side elevation of the personal security device of FIG. 1;

FIG. 6 is a left side elevation of the personal security device of FIG. 1;

FIG. 7 is a top plan of the personal security device of FIG. 1; and,

FIG. 8 is a bottom plan of the personal security device of FIG. 1.

Features shown in broken lines form no part of the claimed design. The design is symmetrical about a vertical plane that bisects the left to right width of the design, facilitating ambidextrous comfort and use.
